UNITED STATES PATENT OFFICE

JOSEPH MONFORTS AND FRANZ WIRTZ, OF MUNICH-GLADBACH, GERMANY, ASSIGNORS
TO A. MONFORTS, OF MUNICH-GLADBACH, GERMANY, A CORPORATION OF GERMANY

CLOTH DOUBLING MACHINE

Application filed November 17, 1931, Serial No. 575,596, and in Germany December 11, 1930.

Our invention relates to cloth doubling machines of the kind in which the travel of the edges of the web is automatically regulated and guide bars serving to fold the web are provided stationarily while pairs of guide rollers 5 for each edge of the web are disposed above these bars which rollers are controlled electro-magnetically, a feeling mechanism being provided the feelers of which are acted upon by the web and regulate the travel of the web. Our invention has for its object to improve this feeler mechanism which is of the design forming the subject-matter of our co-pending patent application Serial Number 418,368. This improvement consists in the fact that the swing member carrying the feeler mechanism is provided with a feeling rocker which is adapted to rock about a vertical axis and carries two contact places so that the two edges of the web act upon one and the same feeler. This arrangement results in the fact that the whole arrangement is notably simplified, is more easily to survey and more reliable in operation.

In order that our invention may be clearly understood and readily carried into effect, an embodiment of the same is illustrated by way of example in the accompanying drawings in which—

Figure 1 is an elevation of a doubling machine fitted with the above-mentioned edge regulating mechanism,

Figure 2 is a fragmentary top view thereof,

Figure 3 is an elevation of a pair of edge 35 guide rollers used, on an enlarged scale,

Figure 4 is an elevation showing the feeling mechanism designed in accordance with the invention, likewise on enlarged scale,

Figure 5 is a top view thereof,

Figure 6 is a detail showing the feeling rocker in top view, with the appurtenant parts of the mechanism,

Figure 7 is a side elevation thereof, and

Figure 8 shows the wiring diagram of the 45 whole arrangement.

Referring to these drawings, 9 denotes the usual doubling table below which are arranged the two stationary folding bars 10. On these bars or on any other suitable carrier 50 is mounted a fixed member 11 which has

mounted on it both the feeler mechanism and the carrier of the guide rollers 12 with the electro-magnets 13.

The construction of the guide rollers and the effect of the electro-magnets on them is 55 well known and therefore need not be described all the more as these members do not form part of our present invention, the latter relating merely to the feeling mechanism.

This feeling mechanism is designed in the 60 following manner:

The stationary member or support 11 has mounted on it a bar 24a which is adapted to be adjusted in various directions and has its free end forked, as to be seen best in Figures 65 4 and 5. A bar 16 which has an adjustable counterweight 15 at top, is swingingly mounted about journals 14 in this forked end. This bar 16 and said bar 24a may be hollow. The lower end of the swing bar 16 is horizontally bent and carries on its vertical portion a rocker 17 of adequate width adapted to rock about its center. The end 16a of bar 16 is bent off horizontally, Fig. 4, and has rigidly mounted on it an adjustable cross 70 75 piece 18 preferably made of an insulating material and carrying two electric contact pieces 19, 20, whilst the rocker 17 has mounted on it two corresponding contact pieces 21, 22.

As to be seen from Figure 8, these contacts 80 are electrically connected in the following manner:

The contact piece 19 of the cross piece 18 is connected through a wire *a* with the electro-magnet 13 and through a wire *b* for instance 85 with the plus pole of a source of current *c*. In a similar manner the contact piece 20 is connected through a wire *a*¹ with the other electro-magnet 13 and through a wire *b*¹ likewise with the plus pole of the source of current. The feeling rocker 16 which is in metallic connection with the bar 16 and through the latter with the bar 24a, is connected to the negative pole of the source of current through a 90 wire *d*. The wires *a*, *a*¹ coming from the contact pieces 19, 20 may pass through the hollow swing bar 16 and hollow bar 24a so that at those places where movable parts are present, no wire runs outside.

The described arrangement operates as follows:

The bars 24a and 16 are adjusted first in the head 23 of the support 11 in such a manner that the swing bar 16 is freely suspended vertically when the folded web travels in its normal position. When the two edges of the web, marked by x and y in Figure 6, exactly register with one another during their downward travel, then they uniformly touch the rocker 17 so that both contacts 19, 21 and 20, 22 remain open. When however for instance the edge x deviates from its normal position relatively to edge y , as indicated by the arrow in Figure 6, the rocker 17 swings horizontally about the bar 16 so that the contact 19, 21 is closed, whilst contact 20, 22 is opened still farther. As a result, the electro-magnet belonging to the closed contact 19, 21 actuates its pair of guide rollers 12. As soon as the edge x returns to normal position under the known action of the respective pair of rollers, the two edges x , y again uniformly act upon the rocker 17 so that both contacts are open again. When the width of the web varies, so that both edges x , y advance while registering with one another, they uniformly act upon the rocker 17 so that in this case too both contacts remain open, one or the other thereof being closed only when the respective web edge advances.

As easily to be understood from the foregoing, the described contact making play in every case takes place satisfactorily and reliably, no matter whether the width of the web becomes greater or smaller. In order to keep flat the edges of the web, especially with thin webs, a usual guiding and straightening bar 24 is made use of, as illustrated in Figure 4, which serves to permanently hold the web edges in the same travelling position relatively to the feeler mechanism described.

What we claim and desire to secure by Letters Patent is:

1. In a machine of the class described means for automatically regulating the travel of the web edges comprising fixed folding bars and electrically controlled pairs of guide rollers for each of the web edges, and a feeling mechanism adapted to trip the electric control of said rollers and comprising a vertically suspended swing bar, a rocker mounted thereon for swing motion about a vertical axis in the range of the adjacent edges of the folded web, and contact pieces on said rocker cooperable with fixed contact pieces, to control the electric controlling means of said rollers.

2. In a machine of the class described means for automatically regulating the travel of the web edges comprising fixed folding bars and electrically controlled pairs of guide rollers for each of the web edges, and a feeling mechanism adapted to trip the electric control of said rollers and comprising a ver-

tically suspended swing bar, a rocker mounted thereon for swing motion about a vertical axis in the range of the adjacent edges of the folded web, contact pieces on said rocker, a cross piece rigidly fixed on said swing bar opposite said rocker, and contact pieces on said cross piece cooperable with said first-named contact pieces to control the electric controlling means of said rollers.

The foregoing specification signed at Cologne, Germany, this 4th day of November, 1931.

JOSEPH MONFORTS.
FRANZ WIRTZ.
